(57) **CLAIM**

The ornamental design for a beverage container, as shown and described.

DESCRIPTION

FIG. 1 is a perspective view of a first embodiment of a beverage container showing the new design; FIG. 2 is a side elevational view thereof; FIG. 3 is another side elevational view thereof; FIG. 4 is another side elevational view thereof; FIG. 5 is another side elevational view thereof; FIG. 6 is a top plan view thereof; and FIG. 7 is a bottom plan view thereof.

FIG. 8 is a perspective view of a second embodiment of a beverage container showing the new design.

FIG. 9 is a side elevational view thereof; FIG. 10 is another side elevational view thereof; FIG. 11 is another side elevational view thereof; FIG. 12 is another side elevational view thereof; FIG. 13 is a top plan view thereof; and, FIG. 14 is a bottom plan view thereof.

The dashed lines shown in the drawings illustrate portions of the beverage container that are not presently claimed and thus form no part of the presently claimed design. The shading lines shown in the drawings represent the approximate three-dimensional contour of the claimed design and are not intended to indicate surface decoration.
